(57) CLAIM

The ornamental design for a trailer-hitch flagpole, as shown and described.

DESCRIPTION

FIG. 1 shows a perspective view of a first embodiment of a design for a trailer-hitch flagpole.

FIG. 2 shows a right side view of the first embodiment.

FIG. 3 shows a left side view of the first embodiment.

FIG. 4 shows a back view of the first embodiment.

FIG. 5 shows a front view of the first embodiment.

FIG. 6 shows a top view of the first embodiment.

FIG. 7 shows a bottom view of the first embodiment.

FIG. 8 shows a view of the first embodiment of the trailer-hitch flagpole when placed in a hitch of an automobile.

FIG. 9 shows a perspective view of a second embodiment of a design for a trailer-hitch flagpole.

FIG. 10 shows a right side view of the second embodiment.

FIG. 11 shows a left side view of the second embodiment.

FIG. 12 shows a back view of the second embodiment.

FIG. 13 shows a front view of the second embodiment.

FIG. 14 shows a top view of the second embodiment.

FIG. 15 shows a bottom view of the second embodiment; and,

FIG. 16 shows a view of the second embodiment of the trailer-hitch flagpole when placed in a hitch of an automobile.

The broken-line features in the figures are for illustrative purposes only and form no part of the claimed design.
